(57) **CLAIM**

The ornamental design for a camera, as shown and described.

DESCRIPTION

FIG. 1 is a top, front, and right side perspective view of a camera showing our new design;

FIG. 2 is a bottom, rear, and left side perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines depict portions of the camera in which the design is embodied that form no part of the claimed design. The break lines depicted with broken lines in the drawings are included to show a symbolic break and the appearance of any portion of the article between the break lines forms no part of the claimed design.
